UNITED STATES PATENT OFFICE.

FREDERIC S. KOCHENDORFER, OF CHICAGO, AND BRUNO E. BALDUF, OF CICERO, ILLINOIS, ASSIGNORS TO WESTERN ELECTRIC COMPANY, INCORPORATED, OF NEW YORK, N. Y., A CORPORATION OF NEW YORK.

ANNEALING-FURNACE.

1,352,459.

Specification of Letters Patent. Patented Sept. 14, 1920.

Application filed September 10, 1918. Serial No. 253,386.

To all whom it may concern:

Be it known that we, FREDERIC S. KOCHENDORFER and BRUNO E. BALDUF, citizens of the United States, residing at Chicago and 5 Cicero, respectively, in the county of Cook and State of Illinois, have invented certain new and useful Improvements in Annealing-Furnaces, of which the following is a full, clear, concise, and exact description.

10 This invention relates to annealing furnaces, and more particularly to a furnace for annealing materials having a bright surface.

The object of this invention is to provide an annealing furnace for bright surfaced materials, by means of which such materials may be rapidly and thoroughly annealed without oxidizing or without having the surfaces marred by water spots.

20 In accordance with the general features of this invention, there is provided an annealing furnace comprising generally an annealing tube divided into zones for annealing and cooling the material and thoroughly 25 drying it before exposing it to the atmosphere. More specifically, the furnace of this invention comprises a tube which opens into a water tank at its receiving end and into the air at its discharge end. Surrounding 30 the tube intermediate its ends are a heating means for raising the temperature of the material to be annealed and cooling means by means of which the temperature of the annealed material is lowered below 35 the temperature of oxidation before it reaches the discharge end of the tube. Superheated steam is introduced into the tube at the receiving end, and the discharge end of the tube is bent over so that the steam 40 will seal the tube against ingress of air. The steam introduced into the tube at the receiving end is condensed by the cooling means surrounding the tube and drawn off at the discharge end.

45 In the drawings illustrating this invention:

Figure 1 is a view in side elevation of an annealing furnace made in accordance with this invention, and

50 Fig. 2 is a fragmentary cross-sectional view illustrating the parts shown in Fig. 1.

As shown in the drawings 5 designates a tube of suitable heat resisting material which has one end 6 opening into a water

seal 7. At its opposite end 8 the tube 5 is inclined downwardly and is open to the air. Surrounding the tube 5 near the end 7 is a heating element 9 comprising a wall 10 of fire clay, which wall is also surrounded by a wall 11 of heat resisting material such as that known in the trade as Sil-O-Cel. Located in the chamber between the walls 10 and 11 are a plurality of gas burners 13-13 by means of which the interior of the tube 5 may be raised to a temperature sufficient to anneal the material passing through it.

Beyond the heating element 9 and surrounding the major portion of the tube 5 is a water jacket 15 having inlet and outlet pipes 16 and 17.

At the receiving end of the tube 5 is a steam inlet 18 connected with a superheating coil 19 located within the heating chamber.

Extending through the tube 5 and beneath a supporting frame 25 is an endless belt carrier 26 driven by means of a motor 27 and adapted to carry the material to be annealed through the tube 5. In the particular application of this invention illustrated, the carrier 26 is shown as conveying metal spools 28 through the tube 5.

An asbestos covering 30 may be placed around the tube 5 at the receiving end thereof and an opening 31 is provided through this asbestos covering and the tube 5 for receiving a thermo couple.

In the operation of the apparatus of this invention metal spools containing bright copper wire or other material may be inserted into the tube 5 through the water seal 7 into which the end 6 of the tube opens, and the movement of the conveyer 26 will draw these spools up into and through the tube 5 to the discharge end 8. As the spools are thus passed through the tube 5 their contents will first be heated to an annealing temperature by their passage through the heating element 10. As they leave the heating element they will enter the zone surrounded by the water jacket 15, through which water is continually flowing, and will gradually be cooled as they approach the end of the tube 5 to a temperature which is lower than the temperature at which the copper would ordinarily be oxidized. The superheated steam which is introduced into

the tube at the receiving end will remove all of the moisture from the spools as they leave the water seal 7 and this steam will be gradually cooled as it comes into contact with 5 the zone surrounded by the water jacket 15 until it is practically all condensed by the time that it reaches the open end of the tube 5. The pressure of this steam, however, throughout the tube 5 will, due to the fact 10 that the discharge end of the tube is bent downwardly, be sufficient to exclude the air therefrom up to a point beyond the zone of the water jacket 15, at which point the spools will be cooled to a point where they 15 will not oxidize upon contact with the air. The water of condensation may be drawn out through a drain pipe 36 adjacent the open end of the tube 5.

The advantages of this construction are 20 that oxidation or discoloring of the wire is avoided by reason of the fact that the wire is absolutely prevented from contact with the atmosphere until it has been cooled below a temperature at which it would ordinarily oxidize or discolor, and because of 25 the fact that the wire or material is thoroughly dried before it reaches the open end of the tube it will not be discolored or spotted, due to water remaining on it after 30 it has passed through the cooling stage. The use of steam for sealing the discharge end of the tube simplifies the operation of the furnace and permits of a practically uninterrupted operation of the mechanism.

35 What is claimed is:

1. In an annealing furnace, a tube through which the material to be annealed is passed, a water seal into which one end of said tube opens, the other end of said 40 tube opening into the air, means for sealing the greater portion of the tubular area from the outside air, means for raising the material to an annealing temperature in one portion of the sealed area, and means for 45 cooling said material below the temperature of oxidation in another portion of said sealed area.

2. In an annealing furnace, a tube through which the material to be annealed is passed, a water seal into which one end of 50 the tube opens, the other end of said tube opening into the air, means for sealing the greater portion of the tubular area from the outside air, a heating element adjacent one 55 portion of said tube for raising the material to an annealing temperature in one portion of the sealed area, and a cooling chamber surrounding said tube to cool said material below the temperature of oxidation in an 60 other portion of the sealed area.

3. In an annealing furnace, a tube

through which the material to be annealed is passed, a water seal into which one end of the tube opens the other end of said tube opening into the air, means located at one 65 end of the tube for excluding the air from the greater portion of the tubular area, a heating chamber located at one end of the tube for raising the material to an annealing temperature, and a cooling chamber 70 surrounding said tube at the opposite end thereof to cool the annealed material below the temperature of oxidation.

4. In an annealing furnace, a tube through which the material to be annealed is 75 passed, a water seal into which the receiving end of said tube opens, the discharge end of said tube opening into the air, a heating chamber located near the receiving end of said tube, a cooling chamber surrounding 80 said tube beyond the heating chamber, and means for introducing steam into said tube to seal it against the air.

5. In an annealing furnace, a tube through which the material to be annealed is 85 passed, a water seal into which the receiving end of the tube opens the other end of said tube opening into the air, a heating chamber surrounding said tube near the receiving end thereof, a cooling chamber surrounding 90 said tube beyond the heating chamber, and means for introducing superheated steam into said tube to dry the material and seal said tube against ingress of air.

6. In an annealing furnace, a tube 95 through which the material to be annealed is passed, a water seal into which the receiving end of the tube opens, the discharge end of said tube opening into the air, a heating chamber surrounding the tube near the 100 receiving end thereof, a cooling chamber surrounding said tube beyond the heating chamber, means for introducing superheated steam into said tube to be led past said cooling chamber, and means for drawing off the water of condensation from said tube.

7. In an annealing furnace, a tube through which the material to be annealed is passed, a water seal into which the receiving end of said tube opens, the discharge end of said tube being inclined downwardly 110 and opening into the air, heating and cooling chambers surrounding said tube, and means for passing steam through said tube 115 from the receiving to the discharge end.

In witness whereof, we hereunto subscribe our names this 24th day of August A. D., 1918.

FREDERIC S. KOCHENDORFER.
BRUNO E. BALDUF.
